UNITED STATES PATENT OFFICE.

GROVER C. MASSEY, OF ANSTED, WEST VIRGINIA.

HOLDER FOR EXPLOSIVE CAPS.

1,329,986.

Specification of Letters Patent.

Patented Feb. 3, 1920.

Application filed January 6, 1919. Serial No. 269,874.

To all whom it may concern:

Be it known that I, GROVER C. MASSEY, a citizen of the United States, residing at Ansted, in the county of Fayette and State 5 of West Virginia, have invented a new and useful Holder for Explosive Caps, of which the following is a specification.

This invention relates to a holder for explosive caps such as used in mining. Under 10 the mining laws of many localities miners are forbidden to ride on cars with dynamite caps or the like on their persons and a miner is also prevented from carrying at one time more caps than are necessary for one day's 15 work. These restrictions are imposed because of the danger not only to the person carrying the caps but to others nearby should the caps explode.

It is an object of the present invention 20 to provide a holder whereby a number of the caps can be carried with safety, said holder being simple and compact and providing convenient access to the contents thereof.

25 With the foregoing and other objects in view which will appear as the description proceeds, the invention consists of certain novel details of construction and combinations of parts which will be hereafter more 30 fully described and pointed out in the claim it being understood that various changes may be made in the construction and arrangement of the parts without departing from the spirit, or sacrificing any of the advantages of the invention as set forth in the 35 appended claim.

In the accompanying drawings the preferred form of the invention has been shown.

In said drawings:

40 Figure 1— is a plan view of the holder embodying the present improvements.

Fig. 2— is a plan view thereof with the cover removed.

Fig. 3— is a section on line 3—3 Fig. 2.

45 Fig. 4— is a section on line 4—4 in Fig. 3.

Referring to the figures by characters of reference 1 designates a block of wood or the like preferably oblong and provided along the side of its top with ribs 2 so that

50 a broad depression 3 is thus formed between the ribs. A pin 4 preferably of wood is secured within the middle portion of the block and extends upwardly from the center

of the top thereof, there being a slot 5 within the upper portion of the pin. Extending 55 downwardly into the block at each side of the center thereof is a group of recesses or pockets 6 each of these recesses is preferably cylindrical. A lining 7 of flannel or other soft material completely covers the wall and 60 the bottom of each recess and also extends partly over the top of the block, this lining being held in place preferably by an adhesive.

A cover 8 is provided for the holder and 65 is preferably formed of a wooden block shaped to fit snugly within the depression 3 and upon the ribs 2, there being a center opening 9 in the cover for the reception of the pin 4. A wedge 10 preferably of wood 70 is adapted to be inserted into the slot 5, thus to bind the cover 8 securely in place.

In using the holder the caps are placed one in each of the recesses 6 after which the cover 8, which has a bottom lining 11 of 75 flannel or other soft material is placed on the block 1 and secured by wedge 10.

Thus it will be seen that the caps will be kept out of contact with each other and will be fully protected by the soft linings. As 80 no metal is included in the construction of the holder there is no danger of accidental explosion of any of the caps. Consequently a filled holder can be carried with safety.

What is claimed is:

85 A holder for explosive caps comprising a block of wood or the like having lined cap receiving recesses, the linings being extended over portions of the block, a centering pin extending from the block, said block having a channeled face, a cover detachably seated in said channeled face and having an opening for the reception of the centering pin, there being a lining upon the bottom of the cover adapted to extend over the 90 recesses in the blocks and to bear upon those portions of the recess linings extending over the block, and means engaging the centering pin to hold the cover on the blocks.

95 In testimony that I claim the foregoing 100 as my own, I have hereto affixed my signature in the presence of two witnesses.

GROVER C. MASSEY.
